Inventor:

William H. Cowell
by Chas. T. Randall
Attorney.

UNITED STATES PATENT OFFICE.

WILLIAM H. COWELL, OF WINTHROP, MASSACHUSETTS.

METHOD OF MANUFACTURING STITCH-DOWN SHOES.

Application filed April 10, 1924. Serial No. 705,499.

To all whom it may concern:

Be it known that I, WILLIAM H. COWELL, a citizen of the United States, residing at Winthrop, in the county of Suffolk, State 5 of Massachusetts, have invented a certain new and useful Improvement in Methods of Manufacturing Stitch-Down Shoes, of which the following is a specification, reference being had therein to the accompanying 10 drawings.

The invention has relation to the manufacture of shoes, and in particular to the manufacture of shoes of the class known as stitch-downs, that is to say, shoes in which 15 the sole is secured to the outturned margin of the upper or vamp by stitches passing vertically through such margin and that of the sole.

Heretofore, in making stitch-down shoes 20 containing box toes or stiffeners the practice has been to secure a box toe or stiffener to the under side of an upper prior to the assembling operation, by means of a line of stitches extending transversely across the 25 fore-part of the upper and engaging with the rear edge of the box toe, paste being applied to cause the upper and the box toe to adhere to each other and give stiffness to the toe part of the shoe after the 30 withdrawal of the last. The assembling operation has been performed by applying the combined box toe and upper to a last having a sole attached to the same, pressing the cement-covered margin of the box 35 toe against the margin of the sole, and the cement-covered margin of the upper against the proximate surface of the margin of the box toe, and applying the lasting stitches or tacks by which the parts are held in as- 40 sembled relations. Displacement of the upper and box toe relative to the sole, re- 45 sulting for example in disposing the line of stitches aforesaid at an inclination trans- versely of the shoe, is liable to occur as the marginal portions of the upper and un- 50 shaped box toe or stiffener are being pressed down into shape and proper place, and as the stitches or other lasting fastenings are being applied.

The object of the present invention is to 55 simplify and expedite the assembling of the parts of a stitch-down shoe upon the last, and avoid the liability aforesaid to displacement of the box toe and upper relative to the sole.

The invention comprises an improvement in the method of manufacturing stitch-down shoes which consists in first preparing a unit composed of a sole having a box toe or stiffener attached to the fore-part thereof, 60 then applying the unit thus prepared to a last by inserting the toe of the last within the said box toe, then making fast the heel part of the sole to the last, and then applying the upper and performing the lasting 65 and remaining operations.

The invention consists, further, in an improvement in the manufacture of lined stitch-down shoes.

The invention is illustrated by the accompanying drawings, in which,—

Fig. 1 is an isometric view of a prepared unit made according to the invention.

Fig. 2 shows such a prepared unit applied and secured to a last, the heel part of 75 the latter being partly broken away, a portion of a shoe lining being represented in connection with the fore-part of the last.

Fig. 3 is a top view of the forepart of a 80 stitch-down shoe.

Fig. 4 is a section on line 4—4 of Fig. 3. Having reference to the drawings,—

In accordance with the invention, the box toe or stiffener 1, instead of being combined with the upper or vamp as heretofore prior 85 to the assembling operation, and in its usual unshaped form, is given its final form by pressing or otherwise, and is joined to the fore-part of the sole 2 in its proper position, as in Fig. 1, preferably by means of cement 90 or glue applied to the outturned margin 11 of the box toe, or if desired by means of stitches, staples, or the like fastening devices. The unit thus prepared may be quickly and accurately positioned upon a 95 last 3, as in Fig. 2, by inserting the toe of the last within the box toe or stiffener 1, following which the unit will be made fast to the bottom of the last. A single tack 4 driven through the heel part of the sole, as 100 in Fig. 2, will suffice.

In the operations of assembling, etc., the vamp or upper 6, Figs. 3 and 4, having the underside of its marginal portion coated with cement is drawn over the last, its cement-coated margin is pressed down into place upon the flange of the box toe and the margin of the sole, the lasting stitches 9 or other lasting fastenings are then applied, and the remaining operations are performed 110

in usual manner. Usually, paste or cement is applied over the top surface of the box toe, or a proper portion thereof, before the upper is placed in contact with such surface.

5 My invention not only facilitates and expedites the work, but it obviates the tendency to displacement of the upper, box toe, and vamp seam, such as occurs with undesirable frequency in prior methods of making stitch-down shoes wherein the box toe or stiffener is secured as aforesaid to the vamp.

10 In case it is desired to provide the shoe with a lining 7, Figs. 2 and 4, such lining is first drawn smoothly into place upon the last, and caused to enclose by its margins an inner sole 8 which has been attached to the last in the ordinary manner by tacks, and then a prepared unit such as is shown in 15 Fig. 1 is applied over the lining and the said inner sole 8 as indicated in Figs. 2 and 4, followed by working the vamp or upper into place, etc., as outlined above. As will be apparent, the work is more readily and conveniently performed than when the shoe is 20 assembled, etc., in conformity with the old practices at present followed.

25 Sole 2 may constitute the wear-sole of a finished shoe, or may have an outsole attached thereto.

30 What is claimed as the invention is:—

1. The improvement in the method of manufacturing stitch-down shoes which consists in first preparing a unit comprising a 35 sole having a box toe or stiffener attached

to the forepart thereof, then applying the unit thus prepared to a last by inserting the toe of the last within the said box toe, then making fast the heel part of the sole to the last, and then applying the upper and performing the lasting and remaining operations.

2. The improvement in the method of manufacturing stitch-down shoes which consists in first preparing a unit comprising a 45 sole having a box toe or stiffener attached to the forepart thereof, then applying the unit thus prepared to a last by inserting the toe of the last within the said box toe or stiffener, then securing the heel part of the sole 50 to the last by a single tack, and then applying the upper and performing the lasting and remaining operations.

3. The improvement in the method of manufacturing lined stitch-down shoes 55 which consists in applying an inner sole to a last, drawing a lining into place around the last and fastening the margins of said lining at the exposed surface of said inner sole, preparing a unit comprising a sole 60 having a box toe or stiffener attached to the fore-part thereof, applying the unit thus prepared to the said last by inserting the lining-covered toe of the last within the said box toe or stiffener, making fast the heel 65 part of the said unit to the last, and then performing the lasting and remaining operations.

WILLIAM H. COWELL.
